(57) **CLAIM**

The ornamental design for a garment, as shown and described.

DESCRIPTION

FIG. 1 is a front view of a garment according to the design; FIG. 2 is a rear view thereof; FIG. 3 is a right side view thereof; FIG. 4 is a left side view thereof; FIG. 5 is a front perspective view thereof; FIG. 6 is a rear perspective view thereof; and, FIG. 7 is a front view thereof shown in an environment of use.

The portions of the garment shown in dash-dot broken lines in FIGS. 1-7 do not form part of the claimed design. The dash-dot broken line showing of the feet, arms, and torso in FIG. 7 is for the purpose of illustrating portions of the environmental structure and forms no part of the claimed design. The dash-dot broken lines define the bounds of the claimed design and form no part thereof.
